PULLING-ON MACHINE

Jacob S. Kamborian, West Newton, Mass.

Application March 24, 1944, Serial No. 527,890

6 Claims. (Cl. 12—1)

1

This invention pertains to the manufacture of footwear, and relates more particularly to a machine for lasting shoes of the force-lasted or slip-lasted type. Slip-lasted shoes usually have a very flexible insole or "sock-lining," the margin of which is permanently united directly to the shoe upper before lasting, the upper being cut without substantial lasting allowance. When the sock lining and upper have thus been united, a last can only be introduced into the shoe by distending and stretching the upper, this stretching of the upper by the introduction of the last constituting the entire lasting operation. Usually the last is introduced into the upper by hand, the operator inserting the toe portion of the last into the upper and then with his hands frictionally urging and pulling the forepart of the upper onto the last in much the same way that a tight glove is pulled onto the hand. As a shoe making operation, this slip or force lasting is laborious, fatiguing and slow and adds materially to the difficulty and cost of making shoes of this type. The present invention has for its principal object the provision of mechanism whereby the operation of slip lasting is facilitated; is made better and more uniform; the labor and fatigue greatly decreased, and the cost reduced. Other and further objects and advantages of the invention will be pointed out in the following more detailed description and by reference to the accompanying drawings wherein

Fig. 1 is a plan view illustrating the apparatus of the present invention;

Fig. 2 is a side elevation of the apparatus;

Fig. 3 is a rear elevation looking forwardly from the rear end of a last mounted in the machine, the upper wiping elements being shown in operative position; and

Fig. 4 is a view similar to Fig. 3, with certain parts broken away, showing the upper-engaging pads separated to facilitate removal of the lasted shoe.

Referring to the drawings the number 1 designates a bench or support upon which is mounted the base 2 of the machine. Near the rear end of the base there is arranged a pedestal 3 comprising an upwardly extending, screw-threaded post 4 which receives a screw-threaded adjusting nut 5 carrying the last-supporting pin 6 on which the last L may be mounted. Preferably, as shown in Figs. 3 and 4, the pedestal 3 is provided with a pair of downwardly directed parallel spaced ears 7 which extend down through an opening in the base 2 and into a registering opening 10 in the bench 1 and which support a

2

pivot pin 8 on which is mounted a grooved pulley 9.

The base 2 is provided with spaced, rigid, parallel guide members 11 and 12, furnished at their inner edges with slots which receive the opposite edges respectively of a slide 13 capable of moving from front to rear relatively to the base member 2. The forward edge of this slide 13 is provided with a member 14 (Fig. 1) to which is attached one end of a flexible cable 15. This cable passes over the pulley 9 and downwardly through the opening 10 in the base and is connected at its lower end to a treadle (not shown) which may be actuated by the foot of the operator thereby to pull the slide 13 rearwardly. A tension spring 16 (Fig. 1) is connected at one end to the forward end of the slide 13 and at its opposite end to a post 17 projecting upwardly from a collar 18 adjustably mounted on a rigid rod 19 projecting forwardly from the base 2. The spring 16 constantly tends to move the slide 13 forwardly and to retain it in its normal or inoperative position.

Mounted on the slide 13 is a support 20 which is connected to the slide 13 by a pivot bolt 20^a (Fig. 1) in such a way that the support 20 is free to swivel about the vertical axis of the bolt. Adjacent to its opposite edges the support 20 is furnished with pairs of upstanding lugs 21 (Fig. 3) which receive the opposite ends of pivot or hinge pins 22, 22^a (Fig. 4) respectively, the axes of these pins being substantially parallel to the guides 11 and 12 and the axis of the last L when the latter operatively is mounted in the machine. Upstanding rigid wing members 23 and 23^a are pivotally supported by the hinge pins 22 and 22^a respectively. These wing members are so shaped that while their lower ends turn or swing about the parallel hinge pins 22 and 22^a their upper parts are inclined relatively to each other diverging from each other toward the rear end of the machine as shown in Fig. 1. At the inner surface of the upper part of each of the wings 23 and 23^a there is mounted an upper pulling element 24 and 24^a respectively (Fig. 4), these pulling elements being here shown as friction pads, for example of crepe rubber or the like, the respective pads being held in place on the wings by means of flanged retainers 25, 25^a, for instance of sheet metal, secured to the respective wings by screws or rivets.

Forwardly of the support 20 there is arranged a rigid upright post 26 (Fig. 2) having a forwardly directed substantially horizontal bracket 26^a which carries a second, shorter post 26^b parallel

to the post 26. The posts 26 and 26^b have bearing openings for a shaft 27 to whose rearward end there is fixed a rigid lever having oppositely directed arms 27^a and 27^b, (Figs. 3 and 4). An actuating arm 28, integral with this lever, extends laterally and is of substantial length so as to afford good leverage and at its outer end is provided with a hand-engaging element 29. A link 30 is pivotally connected to the lever arm 27^b and also to the wing 23^a, while a similar link 31 is connected to the arm 27^a of the lever and to the wing 23. Tension springs S and S' (Fig. 1) constantly urge the wings 23 and 23^a toward each other. The spring S' is shown (Fig. 1) as connected at one end to a screw-threaded rod 32 which extends through an opening in the wing 23^a and is engaged by a wing nut 33 whereby the tension of the spring may be varied. The spring S may likewise be provided with adjusting means if desired. By adjusting these springs the force urging the pads 24 and 24^a toward each other may be varied.

At its upper end the post 26 carries a transversely extending pivot pin 34 on which is mounted a lever having the rearwardly directed arm 34^a and the forwardly directed arm 35. The arm 35 is provided at one side (Fig. 1) with a pair of spaced lugs 36 which receive a pivot pin 37 which passes through an opening in a head 38 at the upper end of a link 39 whose lower end is pivotally secured to an arm 40 fixed to the shaft 27.

A screw-threaded adjusting bolt 41 has threaded engagement with an opening in the forward end of the bracket 26^a and is provided with a knurled head 42 at its upper end. An adjustable collar 43 is mounted on this bolt 41 and forms an abutment for the lower end of a compression spring 44 whose upper end engages the lever arm 35 thus constantly tending to lift the arm 35. The rearward arm 34^a of this lever is provided with a resilient pad 45, for example of crepe rubber or the like, which is wrapped around or otherwise mounted on the end of the arm 34^a and which preferably embraces a rigid transverse filler member 47, the pad being secured to the arm 34^a by a screw or screws 46.

In the operation of the machine, and assuming that the slide 13 is in the normal or forward inoperative position, the operator will take an unlasted shoe comprising a sock lining or inner sole having an upper united thereto, and will draw this shoe over the toe portion of the last L mounted on the post 7, pulling the shoe as far backwardly on the last as can easily be accomplished by hand. The operator then places his foot on the treadle thus gradually drawing the slide 13 rearwardly. The divergent pads 24 and 24^a, together with the pad 45, are thus caused to move rearwardly, the pads 24 and 24^a engaging the upper at opposite sides of the forepart of the last while the pad 45 engages the sock lining. As the slide 13 continues to move rearwardly, the frictional drag of the pads 24, 24^a and 45 on the upper material and sock lining draw the shoe snugly about the forepart of the last so as to stretch the upper and eventually to dispose the toe of the last within the extreme toe of the upper. During this operation the pads 24 and 24^a swing apart to some extent, but being urged toward each other by the spring S and S' 70 exert a heavy pressure against the upper, thus frictionally dragging the upper rearwardly over the last. When the toe of the last has been disposed in the extreme forward end of the upper, the operator then pulls the heel portion of the

shoe down over the heel of the last thus completing the lasting operation. In performing this last named step, the operator may use a shoe horn (Fig. 1) to assist in getting the heel portion of an upper over the heel of the last. Such a shoe horn H may be supported in convenient position for use by a chain C or other appropriate means, or may be mounted for mechanical operation, as by the use of a treadle or the like, if desired. Having drawn the upper down over the heel of the last, the operator then depresses the lever arm 28, thus, by means of the links 30, 31 and 39, disengaging the pads 24, 24^a and 45 from the shoe, so that when the slide 13 is released to resume its normal forward position the pads do not exert any dragging action on the shoe upper during the return of the parts to normal position.

While one desirable embodiment of the invention has been disclosed by way of example it is to be understood that the invention is not necessarily limited to this precise construction but is to be regarded as broadly inclusive of any and all equivalent arrangements.

I claim:

1. In a machine of the class described, a base and a last support fixedly mounted therein, a slide mounted in guides on the base for movement toward and from the last support, means for moving the slide forwardly away from the last support, and means whereby the slide may be moved rearwardly toward the last support, a pair of spaced rigid wings hinged at their lower edges to the slide, the wing axes being substantially parallel to the direction of movement of the slide, but the upper portions of the wings diverging rearwardly, an upper-pulling element carried by each wing, spring means urging the upper ends of the wings toward each other, a lever carried by the slide, the pivotal axis of the lever extending transversely of the slide, a pressure pad carried by one arm of the lever, and adjustable spring means acting upon the opposite arm of the lever to urge the pad downwardly toward the bottom of a last mounted on the last support.

2. In a machine of the class described, a base and a last support fixedly mounted therein, a slide mounted in guides on the base for movement toward and from the last support, means tending to move the slide forwardly away from the last support, and means whereby the slide may be moved rearwardly toward the last support, a pair of spaced rigid upright wings hinged at their lower edges to the slide, the upper portions of the wings being relatively inclined and diverging rearwardly, a friction pad secured to the inner surface of each wing, spring means urging the wings toward each other, and means operative at will to move the upper portions of the wings apart.

3. In a machine of the class described, a base and a last support fixedly mounted therein, a slide mounted in guides on the base for movement toward and from the last support, means for moving the slide forwardly away from the last support, and means whereby the slide may be moved rearwardly toward the last support, a pair of spaced rigid upright wings hinged at their lower edges to the slide, the hinge axes being parallel to the direction of movement of the slide but the upper portions of the wings being relatively inclined and diverging rearwardly, the upper portions of the two wings being spaced apart a distance less than the width of

the forepart of the last, a friction pad secured to the inner surface of each wing, spring means opposing swinging of the wings away from each other, and manually actuatable lever means for swinging the wings apart thereby to release a shoe after it has been lasted.

4. In a machine of the class described, a base and a last support fixedly mounted therein, a slide mounted in guides on the base for movement toward and from the last support, means for moving the slide forwardly away from the last support, and means whereby the slide may be moved rearwardly toward the last support, a pair of spaced rigid upright wings hinged at their lower edges to the slide, the upper portions at least of the wings being relatively inclined and diverging rearwardly, a friction pad secured to the inner surface of each wing, spring means tending to swing the wings toward each other, thereby to cause them to engage the opposite sides of a shoe upper and to stress the upper as the slide moves rearwardly, a presser device operative to engage the sock lining of a shoe mounted on the last and to impart rearward lasting stress to the sock lining as the slide moves rearwardly, and manually actuatable means operative concomitantly to move the upper portions of the wings apart and to lift the presser pad thereby to release the shoe after it has been lasted.

5. In a machine of the class described a base and a last support fixedly mounted thereon, a slide mounted in guides on the base for movement toward and from the last support, means for moving the slide forwardly away from the last support, and means whereby the slide may be moved rearwardly toward the last support, a pair of spaced, rigid, upright, pad carriers hinged at their lower edges to the slide, the hinge axes of the pad carriers being parallel but the upper portions of the pad carriers being inclined relatively to each other and diverging rearwardly, means yieldably urging said pad carriers toward each other, a resilient upper-pulling pad secured to the inner side of each pad carrier at the upper

part of the latter, a post mounted on the slide, a lever fulcrumed on the post to swing about an axis extending transversely of the slide, a presser pad carried by the rearwardly directed arm of the lever, adjustable spring means acting on the opposite end of the lever and urging the presser pad downwardly, and manually operable means for moving the upper parts of the pad carriers away from each other and for concomitantly raising the presser pad thereby to release the lasted shoe.

6. In a machine of the class described a base and a last support fixedly mounted thereon, a slide mounted in guides on the base for movement toward and from the last support, spring means tending to move the slide forwardly away from the last support, and means whereby the slide may be positively moved rearwardly toward the last support, a presser device operative to engage the sock lining of a partially lasted shoe and to exert a rearward frictional drag upon the sock lining as the slide is moved rearwardly, and upper-pulling friction elements also carried by the slide and engageable with the opposite sides of the shoe upper, said friction elements exerting a rearward pull on the upper as the slide moves rearwardly thereby to draw the upper snugly about the last, and means for disengaging said upper-pulling elements and presser device from the shoe prior to the return movement of the slide toward its forward position.
